CLOSURE LOCK

Thomas J. Welborn, Lubbock, Tex.

Application May 10, 1946, Serial No. 668,881

6 Claims. (Cl. 292—22)

1

This invention relates to window locks and it has particular reference to locks of such design and construction as to maintain control of the sashes of the window at all times throughout their range of movement.

The principal object of the invention is to provide for a sash window or the like, a temporary lock to hold the sash or sashes against movement in one direction, yet allowing free movement in the opposite direction and a positive means for locking the temporary latch to prevent its operation except by the use of a key. Thus, the sash may be moved to closed position without restraint but it cannot be moved to open position while under the operative influence of the invention.

Another object of the invention is to provide means for readily releasing the temporary latch to allow for free and unrestricted movement of the sashes in both directions and which means is operative to return the temporary latching means to normal position automatically, thus insuring temporarily latched position of the sashes at all times.

Yet another object of the invention is to provide a control for holding the temporary latching means in inoperative position which feature is advantageous when it is necessary to use both hands in manipulating the sashes, as in the case of sashes which are difficult to operate.

This latter means is instantaneously operated and its function is solely to control the action of the temporary latching means as in the specified instances as well as in cases where it is desired to manipulate the sashes without restraint of any character such for example, as when the sashes are washed.

Broadly, the invention comprehends the provision of an improved window lock and latch which is easy to install either in old buildings or during the course of construction of a new building. The invention is simple and economical in construction and positive in operation thus making for security for homes, residences and even business buildings and will discourage burglary and illegal entry into buildings so protected.

With the foregoing objects as paramount, the invention has particular reference to its salient features of construction and arrangement of parts, which will become manifest as the description proceeds, taken in connection with the accompanying drawings, wherein:

Figure 1 is a fragmentary view of a window frame, in the direction of the arrows 1—1 on Fig-

2

ure 3, showing the invention operatively mounted therein.

Figure 2 is a fragmentary section on lines 2—2 on Figure 3, showing a plan view of the invention.

Figure 3 is a fragmentary view of a window casing and sash assembly in vertical elevation, showing the position of the invention thereon.

Figure 4 is a detail view of a rack and pinion and its latching means.

Figure 5 is a view similar to Figure 4 but showing a construction of rack and pinion and locking means for the companion sash.

Figure 6 is a fragmentary detail view showing 15 a portion of the preferred type of rack employed.

Figure 7 is a view of the latch for holding the temporary locking means operative, and

Figure 8 is another view of the device shown 20 in Figure 7 in plan.

Continuing with a more detailed description of the drawings, 1 designates the side jambs of the window frame, in which is mounted in a conventional manner the upper and lower sashes 25 A and B respectively. These sashes are held in sliding relation to the jamb by means of the conventional cleats 2.

On one edge of each sash, there is provided a rack 3, a fragmentary detail view of which is 30 shown in Figure 6. This rack has a flange 4 which reposes within longitudinal grooves provided in one side of each sash and is held therein by suitable means such as nails or screws 5, shown in position in dotted lines in Figure 2. 35 This groove may be made by means of a rotary saw or the like.

Mounted upon a plate 6 is a pair of bearings 7 carrying a transverse shaft 8. On the opposing sides of the bearings 7 the pinions 9 are 40 mounted and which, when the sashes A and B are slidably operative in the window frame, engage the racks 3 in the manner shown in Figures 4 and 5.

It frequently happens that a sash will contract and become loose in its mounting and its sides will consequently withdraw slightly from the track in which it operates. It being essential that the pinion 9 be at all times in mesh with the teeth 10 of the rack 3, it is necessary to provide 45 some means to insure this condition. Accordingly, at each side of the plate 6, there is provided a clip 11 which embraces the edge of the plate and slidably embraces the edge of the rack 3. The rack is thus held in close relation to the plate 6 50 and there is no chance that displacement be-

tween the rack and pinion will occur, particularly since the rack is securely affixed to the sash as previously explained. It is apparent therefore that the sashes may be moved freely in their tracks or channels and in so doing, the pinions 9 are rotated.

In order to control the movement of the sashes, dogs 12 are provided and are pivotally mounted, by means of pins 13 on extended portions 14 of the bearings 7, which carry the shaft 8. Lugs 15, integral with each of the dogs 12 are held in normal engagement between the teeth 16 of the pinion 9 by means of an arm 17 pivoted at a to the plate 6, as in Figure 1. The ends of the arm 17 are free and with the integral portion 18 of the arm, the member may be said to be substantially T-shaped and by moving the upper end of the portion 18 of the member, the free ends of the arm 17 are raised and lowered to actuate the dogs 12 with respect to the pinions 9.

An examination of Figures 4 and 5 will disclose that the dogs 12 are substantially different in construction. This is necessary that they must be simultaneously moved to latched and unlatched relation to the pinions 9 and since the ends of the arm or portion 17 travel in opposite directions when the portion 18 is moved, the dog shown in Figure 4 is moved to unlatched relation with its pinion as the end of the arm 17 moves downwardly while the companion dog shown in Figure 5 is moved to unlatched position simultaneously when the opposite end of the arm 17 moves upwardly. In either case, the weight of the dog alone is effective in maintaining latched position thereof. The dog shown in Figure 4 is illustrated on the right in Figures 1 and 2 while that shown in Figure 5 is on the left. The dotted line position of the dogs 12 in Figures 4 and 5 are the inoperative positions thereof when they are actuated by the arm 17 as explained.

Normally, the dogs 12 are in latched engagement with the pinions, that is to say, they are in such position that the sashes may be moved to closed position under continuous control of the dogs and pinions but the direction of movement of the sashes cannot be reversed until the dogs are both moved out of engagement with the pinions. This is accomplished by means of a plunger 19 carrying a push button 20, slideable in an aperture 21 in the window facing. The inner end of the plunger 19 is threaded into the tubular, bifurcated member 22, non-rotatably supported by a bracket 23 and which member embraces the upper end of the portion 18 of the T-shaped member referred to previously and due to the pivotal engagement at b, the T-shaped member may be oscillated on its pivot point a by pressure upon the push button 20. A weight 24, mounted on the arm 17 of the T-shaped member and offset from the pivot point a thereof returns the parts to normal latched position as soon as pressure is relieved from the button 20. While gravity alone is sufficient to hold the dogs in engaged position with respect to the pinions 9, to secure the same against movement in one direction, it requires the raising of the weight 24 to render the dogs inoperative for free and unrestricted movement of the sashes A and B. A pair of stops 25 are disposed above and below the arm 17 at the left in Figure 1 to limit the movement thereof when the plunger 19 is actuated as explained.

In some cases the sash may become stuck and rendered difficult to move and in other cases a wide sash may be equipped with the invention and in either case, both hands may be required to

manipulate the sashes. It is therefore necessary to provide means for securing the temporary latching means just described in inoperative position while the sashes are adjusted to the required or desired position. This means comprises the detail shown in Figures 7 and 8 which includes a slide 26 disposed behind the escutcheon plate 27 carrying the control elements of the invention. A button 28 is provided to enable the slide 26 to be moved relative to the push button 20 and when it is advanced upon the push button, the end of the slide 26 enters a recess 29 in the push button 20 when the latter has been depressed. Thus, the plunger 19 is held against return to normal position and the dogs 12 are thus held out of operative engagement with the pinions 9. Both hands may therefore be used to manipulate the sashes A and B until the desired adjustment is obtained, whereupon the button 28 may be moved away from the button 20 to release the latter and the weight 24 will return the elements to normal position automatically.

It is one of the important features of the present invention that one or both of the sashes may be partially opened and locked to prevent entry of a person yet allowing for ventilation. It is understood however, that at no time are the sashes locked against movement to closed position. This is provided for in case it is necessary to close 30 the window hurriedly and the key is not immediately available.

In order to positively lock the sashes in partial, full open or full closed position, a plunger 30 is provided and controlled by a key, not shown, 35 inserted into the cylinder 31. The type of key lock employed is conventional but is preferably a spring lock which is depressed when in locked position and its plunger 30 is automatically retracted by means of a spring 32 when unlocked. 40 When in locked position, the inner end of the plunger 30 lies in the path of the weight 24, carried by the arm 17, thereby preventing movement of the arm, thus maintaining the dogs 12 in engagement with the pinions 9, which relationship prevents rotation of the pinions in one direction but does not interfere with their opposite rotation. The dotted position of the plunger 30 in Figure 1 shows the locked position of the invention when the lock 31 is actuated by a key. When unlocked, the spring 32 returns the plunger to the solid line position shown in Figure 1 and the elements of the invention are free to operate as previously explained.

In installing the invention in an old house, it is simply necessary to remove the cleats 2 to effect removal of the sashes A and B. One edge of each sash is slotted to receive the flange 4 of the rack 3, whereupon the rack is mounted in the manner explained and shown in Figure 2. A suitable opening is made in the jamb at a point parallel to the meeting rails of the sashes and the mounting plate 6 of the invention is so secured to the jamb by means of screws 33 that it will be flush with the surface of the jamb. The elements of the invention are operatively disposed within the jamb but before the plate is secured in position, holes are bored in the facing to accommodate the locking elements, such as the plungers 19 and 30. When the latter plunger is in place, the plate 6 is moved until the weight 24 engages the extended end of the plunger 30, which must be in locked position. After this is done, the plunger 19 is passed through the opening 21 in the facing and screwed into position in relation to the bi-

furcated tubular member 22. The mounting plate 6 may then be secured.

The sashes are now ready to be mounted in the frame but in order to mount the sashes, it is necessary that the ends of the rack 3 be so constructed as to allow the teeth of the pinions 9 to align with the apertures 10 of the rack. This is accomplished by cutting the apertures of the lower sash rack out to the edge at the bottom as at c in Figure 6 and the upper sash rack is similarly cut but at the top. Thus the upper sash must be set in below the meeting rail and moved to its proper position. By so cutting the racks, they are not weakened. The sashes may thus be placed in operative position in the frame without interference by the pinions 9 since the teeth thereof freely enter the slots c of the rack and the line with the aperture 10 thereof. It will be understood that in mounting the sashes, the rack 3 must be inserted under the clip 11 as explained previously so that the rack will be at all times in operative relation with the pinions. After the cleats 2 have been replaced, the invention is ready for operation.

In mounting the invention for operation in buildings during the period of construction, substantially the same directions will be followed except that installation will probably be made whenever the window frames are manufactured.

Manifestly, the construction shown is capable of considerable modification and such modification as is considered within the scope and meaning of the appended claims is also considered within the spirit and intent of the invention.

What is claimed is:

1. A sash lock for windows including pinions disposed in the frame of said window with gravity operated dogs to constrain the same to rotate only in one direction, a rack secured to said sash to move therewith and held in operative engagement with said pinions, a weighted arm of substantially inverted T-shape pivotally disposed for operation exteriorly of said frame to render said dogs inoperative to effect free and unrestricted movement of said sash.

2. A sash lock for windows and the like including pinions mounted for rotation in the frame of said window, racks carried by said sash and held in engagement with the teeth of said pinions, gravity operated dogs in normal engagement with said pinions, an inverted T-shaped arm pivoted for oscillative movement whose ends are in engagement with said dogs, and controllable from the exterior face of said frame for holding said sash against movement in one direction, and normally inoperative means for releasing said dogs.

3. A lock for window sashes including pinions rotatably mounted in the frame of said windows and in continuous engagement with racks car-

ried by said sashes, dogs in normal engagement with said pinions for holding the same against movement in one direction, an inverted T-shaped member pivoted for oscillative displacement for moving said dogs to inoperative position with respect to said pinions to effect free movement of said sashes, means for temporarily latching said plate, gravity controlled means resisting oscillative displacement of said pivoted member for returning said dogs to operative position upon release of said temporary latching means.

4. A lock for window sashes and the like including means carried in fixed relation with said sashes in continuous moving engagement with pinions rotatably mounted in concealed position in the frame of said window, dogs for latching said pinions against movement in one direction only, gravity controlled oscillative means exteriorly manipulatable for activating said dogs and means for temporarily securing said dogs for free manipulation of said sashes.

5. A lock for sashes and the like including pinions in the frame of said sashes and in continuous engagement with means in fixed relation with said sashes, oppositely disposed pivoted dogs cooperating with said pinions for holding the same against rotation in one direction and an inverted T-shaped and pivoted arm arranged for manipulation exteriorly of said frame for temporarily rendering said dogs inoperative to release said sashes for unrestricted movement.

6. A lock for dual window sashes including pinions mounted in the frame of said sashes, a rack in fixed relation to each of said sashes with which said pinions are in continuous engagement, a dog controlling each of said pinions for holding the same against rotation in one direction, a single arm operable from a point externally of said sash frame for rendering both of said dogs inoperative simultaneously to effect unrestricted movement of said sashes in said frame, gravity means resisting displacement of said arm in one direction to return said dogs to operative control of said pinions; and means for operatively locking said pinions to secure said sashes against movement to open position.
